UNITED STATES PATENT OFFICE.

ERNST SCHARFF, OF FRANKFORT-ON-THE-MAIN, GERMANY.

SAFETY-RAZOR.

No. 830,105.

Specification of Letters Patent.

Patented Sept. 4, 1906.

Filed April 26, 1904. Serial No. 204,940.

To all whom it may concern:

Be it known that I, ERNST SCHARFF, manufacturer, residing at 18 Fahrgasse, Frankfort-on-the-Main, German Empire, have invented new and useful Improvements in Safety-Razors, of which the following is a specification.

My invention relates to safety-razors, and more especially to the means whereby the razor-blade is clamped in the casing.

In the accompanying drawings, Figure 1 is a perspective view of a safety-razor embodying my invention, and Fig. 2 is a side elevation thereof.

15 *a* is the casing made in the usual way.

r is the razor-blade, which is pressed against the casing by clamps.

f g are the two arms of a bell-crank lever pivoted at the point *c* to the casing. This bell-crank lever is provided at the end *b* with a presser-roll *n*, which forms a practically-unyielding stop to facilitate the placing of the blade into its working position. The end of the lever-arm *g* is screw-threaded and 25 carries a pressing-screw *d*. This screw extends through a hole *h* in the casing and is provided with a head *m* to allow its turning by an appropriate key. By this arrangement of the screw-head *m* at the rear side of 30 the casing it is easily accessible, and yet does not protrude at a place where it could interfere with the working of the razor.

The roller *n* forms a practically-unyielding stop, limiting the forward movement of the 35 blade *r* when the same is inserted, and thus accurately determining the position of the blade relatively to the casing. By means of

the adjusting-screw *d* the position of the presser-roll or stop-roll *n* may be varied so as to allow the blade *r* to be pushed farther 40 forward when its edge has been reduced by grinding.

I am aware that set-screws have been applied to one-armed levers in safety-razors and that bell-crank levers have been used 45 before my invention, especially in connection with springs; but

What I claim as my invention, and desire to protect by Letters Patent, is the following:

1. In a safety-razor, the combination of 50 the casing forming a support for one side of the blade, a practically-unyielding stop arranged to engage the other side of the blade, a bell-crank lever pivoted on the casing at the rear thereof and having one arm carrying 55 said stop, and an adjusting device rigidly connecting the other arm of the bell-crank lever with the casing to move said stop toward or from the adjacent portion of the casing.

2. In a safety-razor the combination of a 60 pressing-lever with a pivotal connection at the rear side of the casing and a pressing-screw protruding through the rear wall of the casing and having a head which bears 65 against said wall.

In testimony whereof I have signed my name to this specification in the presence of two subscribing witnesses.

ERNST SCHARFF.
